ILLUMINATING DEVICE

John A. Hoeveler, Pittsburgh, Pa., assignor to
 Pittsburgh Reflector Company, Pittsburgh,
 Pa., a corporation of New Jersey

Application February 16, 1933, Serial No. 657,008
 Renewed September 22, 1936

4 Claims. (Cl. 240—78)

My invention relates to the art of illumination and, in particular, to an illuminating device of the so-called indirect type.

While numerous types of indirect lighting fixtures are on the market at the present time, I have found that there are many objections to the use of most known types of units. It is generally recognized that indirect illumination is the form of artificial lighting which provides greatest 5 ocular comfort or, to put it another way, causes least ocular fatigue, but there are many who do not like the appearance of the opaque bowl characteristic of such fixtures. I have invented a lighting fixture which overcomes most of the 10 objections inherent in the devices of the prior art and, furthermore, provides several additional 15 advantages of considerable importance.

In accordance with my invention, I provide an 20 opaque bowl having generally the shape of an inverted conical frustum, which is adapted to be suspended from the ceiling. I place a reflector 25 within the bowl for reflecting the major portion of the light upward to the ceiling. The reflector also is provided with a portion which transmits 30 light, which portion may be of clear or translucent glass, or consist merely of an opening in the reflector.

As a closure for the light transmitting portion 35 of the reflector I also provide a cap of colored or colorless material capable of transmitting light and mount a secondary reflective bowl therebelow for the purpose of illuminating the exterior of the first-mentioned bowl. It is possible by the combination described to provide a very 40 excellent illumination for a room from a single fixture and, at the same time, to illuminate the exterior of the opaque bowl so that it has the appearance of a high grade translucent glass whereas, in fact, it may be made of inexpensive, 45 light weight metal.

As a modification of the invention, I may suspend a plurality of auxiliary bowls below the principal or primary bowl and provide for indirect illumination of the exterior of each bowl.

The combination with the opaque bowl of the 45 interior reflector makes it possible to design each member of the combination with a view to the maximum efficiency without compromising between two relatively inconsistent objectives, 50 namely, the most efficient lighting of the room by reflected light and the most attractive display of the fixture itself. Other advantages and novel features of the invention will be pointed out as the description thereof proceeds.

55 My copending application Serial No. 642,255,

filed November 11, 1932, for Reflectors, describes and claims a lighting fixture including an opaque main reflector, an opaque supplemental reflector, and colored means spaced from the latter through which a portion of the light from a 5 source within the main reflector passes and is reflected by the supplemental reflector as colored light on to the exterior of the opaque main reflector.

For a complete understanding of the invention, 10 reference is made to the accompanying drawings illustrating a present preferred embodiment, together with a modified form, although it is obvious that the details of the invention may be changed radically from the present disclosure 15 within the scope of my broader claims. In the drawings:

Figure 1 is a half sectional and half elevational view, partly broken away, of a preferred form of 20 the invention;

Figure 2 is a similar view of a modified form; 25 and

Figure 3 is a partially broken away view similar to Figure 1 showing a further modification.

Referring in detail to the drawings, a lighting 30 fixture indicated generally at 10, comprises a socket husk 11 which may be suspended from the ceiling by any desired type of hanger. The husk encloses a socket (not shown) into which is 35 screwed a conventional type of electric light bulb 12. Arms 13 secured within the husk 11 provide a tripod support for the lighting fixture.

The fixture proper includes a primary bowl 14 of generally frusto-conical shape. The bowl may be of any material and is preferably opaque. It 40 may conveniently be made of spun aluminum sheet of light gauge with etched and lacquered external surface. The bowl 14 has an outwardly extending upper portion 15, an inturned upper flange 16 and a lower flange 17. A supporting 45 ring 18 is seated under the upper flange 16 of the bowl 14 and is provided with lugs 19 for engaging hook portions 20 on the ends of the arms 13.

A reflector 21 has a silvered reflecting portion 45 22 and a transmitting portion 23. The reflector is seated in the ring 18 by the engagement of its rim with a step flange 24 on the inner periphery 50 of the ring.

Below the transmitting portion 23 of the reflector 21, a cap 25 of colored or colorless material capable of transmitting light is supported by the engagement of its edge in the lower flange 55 17 of the bowl 14.

Radial arms 26 extend from the lower edge of 60

the bowl 14 for supporting a secondary bowl 27 having a shape somewhat similar to that of the bowl 14 but somewhat smaller in size. The upper rim 28 of the bowl 27 is slotted at 29 whereby a bayonet connection with the radial arm 26 may be effected.

An annular flange 30 is formed adjacent the lower end of the bowl 27 and is provided with perforations 31. A cross bar 32 is seated on the flange and serves to suspend a crystal 33 and a tertiary bowl 34.

When the bulb 12 is switched on, the major portion of the light therefrom impinges upon the silvered reflecting portion 22 of the reflector 21 and is reflected to the ceiling and thence to all parts of the room in which the fixture is installed. It will be apparent that the reflecting portion of the reflector 21 is of such shape as to reflect the maximum amount of light from the bulb to the ceiling with perfect uniformity. At the same time, a portion of the light from the bulb 12 traverses the light transmitting portion 23 of the reflector and the cap 25, whereupon it impinges upon the interior of the bowl 27. The latter is not brightly polished but has considerable reflecting capacity and as a result, light rays having the color of the cap 25 are reflected from the bowl 27 on to the portion of the bowl 14 between the lower edge of the latter and the out-turned portion 15 thereof.

Light from the bulb 12 also traverses the perforations 31 in the flange 30 adjacent the bottom of the bowl 27 after traversing the light transmitting portion 23 of the reflector 21 and the cap 25. This light is reflected by the bowl 34 on to the exterior portion of the bowl 27 between its lower edge and the out-turned portion thereof. Direct light from the bulb 12 also filters down to and illuminates the crystal 33 which mirrors itself in the bowl 34 and thus high lights the exterior thereof, completing a most attractive display of the fixture.

The appearance of the device just described, when lighted, is quite remarkable. The outer surfaces of the bowls are illuminated with a soft diffused light having the color of the cap 25 which makes the bowls appear exactly as if they were composed of a beautiful, highgrade, lightly translucent glass illuminated from within. The extreme outer portion of the bowls being shaded from the light reflected on the major portion of the exterior thereof, form darkened bands separating the beautifully illuminated portions of the bowls, thus giving the appearance of metal bands in which luminous translucent glass bowls are suspended. The illumination of the crystal 33 completes the effect and the whole structure presents a highly pleasing appearance. At the same time the shape and efficiency of the reflector 21 are such that uniform illumination is provided throughout the room by indirect rays exclusively. Since the fixture may be largely composed of some sheet metal of light gauge, it can be manufactured at comparatively low cost.

Since the primary bowl 14 and the smaller bowl or bowls suspended therefrom are not relied upon to reflect the major portion of the light to the ceiling for a second reflection into the room, it is possible to design the exterior bowl with a view to striking appearance. The reflector 21 itself is concealed and its appearance is immaterial.

By my invention it is possible to provide a fixture which has remarkably efficient illumi-

nating qualities while at the same time is of really outstanding artistic merit. By using a reflector which is separate from the exterior bowl both functionally and physically, I am able to achieve a control of the upwardly reflected light which otherwise would be impossible. The use of a separate, readily removable reflector, furthermore, achieves a permanence of reflecting efficiency because of the ease with which the reflector may be removed for repeated cleaning, without the necessity of otherwise taking the fixture apart. Similarly, since the color is introduced into the light traversing the transmitting portion of the reflector by a cap separate from the reflector, there is no chance of colored light reaching the ceiling to affect the quality of the light in the room.

The structure described is desirable from a mechanical standpoint since it permits a free open space for renewing or changing the lamp bulb, as well as for removing the reflector, although it will be evident that the reflector need not necessarily be removed in order to clean the interior reflecting surface thereof.

Another very important feature of the invention is that the cap 25 may easily be removed and changed so that the entire appearance of the fixture can be altered to suit various decorative schemes at the pleasure of the user. This feature also makes it possible for a standard unit, which may be produced cheaply in quantities, to be employed for a wide variety of situations where hitherto it has been the custom to use specially designed and hence much more expensive fixtures, by accommodating the cap 25 to provide a decoration of the exterior surfaces of the fixture in harmony with the decorations of the particular room in which it is to be installed.

Another important feature of the invention illustrated is that the space between the exterior bowl and the interior reflector may be entirely closed if my preferred one piece reflector 22 having a reflecting portion and also a transmitting portion be employed. The ring 18 extends between the upper edges of the bowl and the reflector and forms a tight closure. The cap 25 tightly closes the bottom opening of the bowl so that the latter, and the reflector, fully enclose the space therebetween. Accumulation of dust is thus prevented.

A modified form of the invention is illustrated in Figure 2. This form of the invention, shown generally at 35, is similar to that already described in that it comprises a socket husk 36 enclosing a socket 37 into which a bulb 38 is screwed. Arms 39 depending from the socket husk support a bowl 40 similar to the bowl 14, through the medium of a ring 41 having lugs 42 received on the hook ends 43 of the arms 39.

A reflector 44 is suspended by its upper edge from the inner edge of the ring 41. The reflector 44 has a reflecting portion 45 and a light transmitting portion 46. It also has a central opening 47. A cap 48 and a disc 49 cover the opening 47 and provide a support for a suspension stud 50. A finial 51 is screwed onto the lower end of the stud 50 and supports an auxiliary or secondary bowl 52 having an upturned annular shoulder 53. A cap 54 performing the same function as cap 25 having a central opening for admitting the stud 50, is supported on the shoulder 53 with its upper edge engaging a flange 55 on the lower edge of the bowl 40. 75

The effect produced by the structure of Figure 2 is similar to that of the device of Figure 1 except that when lighted, it exhibits only one exteriorly illuminated zone. The major portion 5 of the light from the bulb 38, of course, is reflected onto the ceiling by the reflector portion 45 of the reflector 44. The portion of the light traversing the transmitting portion 46 of the reflector also passes through the cap 54 10 and is reflected by the bowl 52 onto the exterior of the bowl 40. It will be apparent that the fixture of Figure 2 will be illuminated exteriorly only between the upper out-turned rim portion thereof and the upper edge of the bowl 52. This 15 combination of light and dark zones constitutes a very desirable decorative effect, and all the aforementioned advantages of the device of Figure 1 are also characteristic of the modified form of the invention shown in Figure 2. The 20 parts are easily assembled to form a tightly closed, rigid structure but at the same time the assembly is such as to permit ready removal or replacement of any part.

By a slight modification of the structure of 25 Figure 1, it is possible to illuminate successive zones of the exterior of the fixture by light of different colors. In Figure 3, I have shown a portion of the device of Figure 1 incorporating this modification. Corresponding parts in Figure 30 have the same reference numerals as in Figure 1 with a prime affixed. The intermediate bowl 27' has its lower end formed to provide a seat 30' for a cap 56. Perforations 31' are formed in the bowl below the seat 30' so that 35 light traversing the cap 56 impinges upon the interior of the third bowl 34'. Light also impinges directly upon the crystal 33' which is suspended on a screw traversing a central hole in the color cap 56.

40 The color of the light reflected upon the exterior of the bowl 27', of course, will depend upon the character of the color of cap 56 and this, in turn, will depend upon the color of the main cap 25. The light passing through the 45 main cap 25, in other words, must contain a sufficient amount of light of the color transmitted by the second cap 56 to properly illuminate the exterior of the bowl 27'. The colors of the two caps may be chosen in accordance 50 with well known laws of light transmission to provide the exterior of the fixture with illuminated zones of different colors. For instance, if an amber cap 25 is used at the bottom of the upper member, the exterior surface thereof 55 will be illuminated with an amber light. However, amber allows plenty of red light to pass through so that a red cap 56 placed at the bottom of the middle member will provide red illumination for the exterior surface thereof and of crystal 33'.

60 Similarly, a light blue color cap at the top with a dark blue at the bottom will give these two tones of blue on the upper and middle members respectively and dark blue in the crystal 33'.

65 Although I have illustrated and described herein but a single present preferred embodiment of the invention together with a slight modification thereof, it will be apparent that

numerous changes in the invention as disclosed will occur to those skilled in the art and may be made without departing from the spirit of the invention or the scope of the appended claims.

5 I claim:

1. In a lighting fixture, the combination with 10 an opaque exterior bowl having an open bottom, an inwardly extending ring seated in the upper edge thereof, the edge of the bowl being turned over the ring, supporting means attached to said ring, and a reflector having a light-transmitting portion, seated on said ring, a color cap closing the open bottom of said bowl and underlying said light-transmitting portion, and means below the 15 cap effective to reflect colored light passing therethrough onto the exterior of said first-mentioned bowl.

2. In a lighting fixture, the combination with 20 an opaque, open-bottom bowl, means extending upwardly from said bowl for supporting it from above, means carried on said supporting means forming a seat within said bowl, a reflector bowl positioned in said seat and having a light- 25 transmitting portion, a second opaque bowl below the first-mentioned bowl and adapted to reflect light passing through the transmitting portion of said reflector on to the exterior of the first-mentioned bowl, and a color filter mounted on said first-mentioned bowl between the transmitting portion of said reflector bowl and the second-mentioned opaque bowl.

3. In a lighting fixture, the combination with 30 an opaque, open-bottomed bowl, means extending upwardly from said bowl for supporting it from above, means carried on said supporting means forming a seat within said bowl, a reflector bowl positioned in said seat, said reflector bowl being of such character as to transmit at 35 least a portion of the light impinging thereon, a second opaque bowl below the first-mentioned bowl and adapted to reflect light passing through said reflector bowl onto the exterior of the first-mentioned bowl, and a color filter mounted on said first-mentioned bowl between said reflector 40 bowl and the second-mentioned opaque bowl.

4. In an illuminating device, the combination with 45 an open bottom, opaque bowl tapering downwardly whereby to permit the exterior illumination thereof by light reflected from below, a light 50 source supported within the bowl, an integral, one-piece reflector suspended in the bowl by its upper edge, said reflector having upper reflecting and lower transmitting portions and being shaped and adapted to reflect the major portion of the 55 light from said source upwardly and outwardly of said bowl and to transmit a minor portion of the light downwardly through the open bottom of the bowl, a second reflector spaced below the open bottom of the bowl adapted to reflect said 60 minor portion of the light onto the exterior of said bowl, said bowl having an inwardly extending flange adjacent its lower end, and a color cap seated therein through which the light traversing at the transmitting portion of the first-mentioned reflector is adapted to pass before being reflected by the second-mentioned reflector 65 onto the exterior of the bowl.

JOHN A. HOEVELER.
